CLAIM

The ornamental design for a toy block, as shown and described.

DESCRIPTION

FIG. 1 is a front perspective view of a toy block according to the present design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a first perspective view illustrating use thereof; and,

FIG. 9 is a second perspective view illustrating use thereof.

The broken lines in FIG. 7 are for the purpose of illustrating portions of the article that form no part of the claimed design. The broken lines showing of parts in FIGS. 8 and 9 are included for the purpose of illustrating use and environment and forms no part of the claimed design.
